R. S. McINTOSH

FLUID PRESSURE BRAKE

Filed Sept. 22, 1926

Inventor

R. S. Mcintosh.

By *Alfred J. Randolph Jr.* Attorney

UNITED STATES PATENT OFFICE.

ROGER SHERMAN McINTOSH, OF HAZARD, KENTUCKY.

FLUID-PRESSURE BRAKE.

Application filed September 22, 1926. Serial No. 137,047.

This invention relates to improvements in fluid pressure brakes, and more particularly to improvements in the E. T. locomotive brake equipment.

5 The invention has for one of its objects to provide novel and simple means adapted to prevent the casual application of the brakes on the locomotive as the result of a variation in the pressure due to a leak in the brake pipe or a faulty or dirty feed valve.

The invention is hereinafter fully described and claimed, and illustrated in the accompanying drawing, wherein:

15 Figure 1 is a view partly in elevation and partly in vertical section illustrating the application of the invention to an E. T. locomotive brake equipment, and

20 Figure 2 is a sectional view taken on the vertical planes indicated by the line 2—2 of Figure 1.

In the drawing, 1 designates the distributing valve, 2 the independent brake valve which is operated by a handle 3 and 4 the release pipe of the E. T. locomotive brake equipment. The distributing valve 1 is provided with an application cylinder 5, an application piston 6, a passage 7 establishing communication between the application cylinder 5 and release pipe 4, and an equalizing slide valve 8. When fluid under pressure is admitted to the application cylinder 5 either by operation of the independent brake valve 2 or by operation of the equalizing slide valve 8, the piston 6 is operated to effect an application of the brakes in a well known manner.

In this type of brake equipment, a variation of pressure, caused for instance by a leak in the brake pipe or a faulty or dirty feed valve, would cause the equalizing piston to move in a direction to cut off communication between the release pipe 4 and application cylinder 5 by closing the passage 7. With the equalizing piston in this position, any leak that would cause air to enter the application cylinder 5 would result in the building up of the pressure in the cylinder and the consequent gradual application of the brakes.

50 In order to prevent this application or creeping or leaking on of the brakes, there is established communication between the release pipe 4 and application cylinder 5 by way of a passage which is entirely independent of the passage 7 and cannot be closed by the equalizing piston. This pas-

9 sage is provided preferably by a pipe 9 which is connected to the distributing valve 1 and release pipe 4 and is in communication with the release pipe and the application cylinder 5 at the left side of the application piston 6. The pipe 9 establishes direct communication between the release pipe 4 and the application cylinder 5, and is provided with a cut out cock 10 for the purpose of cutting off this direct communication between the release pipe and application cylinder on the second engine in double heading. This direct communication between the release pipe 4 and application cylinder 5 makes it 60 impossible for the brakes to creep or leak on and cause the tires of the drivers to heat and slip, even though such conditions as dirty feed valves or small leaks in the brake pipe may obtain. It will not, however, prevent the usual application of the brakes or 70 their application on the opening of the conductor's valve at the rear of the train or their application should the train break in two. Should the brakes be applied as the 80 result of the opening of the conductor's valve or as the result of the breaking in two of the train, the engineer will have ample time to lap the brake valve and hold the 85 brakes applied until the train stops. Furthermore, the invention will, after a service application of the brakes and the return of the brake valve to running position, cause the brakes to release quickly.

What is claimed is:—

1. In a fluid pressure brake, the combination with a distributing valve having an application cylinder and passage communicating with said cylinder, and a release pipe communicating with said passage, and means establishing communication between said pipe and cylinder independently of said passage.

2. In a fluid pressure brake, the combination with a distributing valve having an application cylinder and passage communicating with said cylinder, and a release pipe communicating with said passage, and means establishing communication between said pipe and cylinder independently of said passage, and a cut off valve in the passage established by said means.

3. In a fluid pressure brake, the combination with a distributing valve having an application cylinder and passage communicating with said cylinder, and a release pipe communicating with said passage, of a pipe

establishing direct communication between said pipe and cylinder.

4. In a fluid pressure brake, the combination with a distributing valve having an application cylinder and passage communicating with said cylinder, and a release pipe communicating with said passage, of a pipe establishing direct communication between said pipe and cylinder, and a cut off valve in said pipe.

5. In a fluid pressure brake, a distributing valve having an application cylinder,

passages communicating with the cylinder, and a release pipe communicating with said passages.

6. In a fluid pressure brake, a distributing valve having an application cylinder, passages communicating with the cylinder, a release pipe communicating with said passages, and a cut off valve in one of said passages.

In testimony whereof I affix my signature.

ROGER SHERMAN McINTOSH.
